UNITED STATES PATENT OFFICE

2,494,892

INDICATOR FOR COOKING RANGES

Charles M. Mayer, Mansfield, Ohio, assignor to
The Tappan Stove Company, Mansfield, Ohio,
a corporation of Ohio

Application April 13, 1948, Serial No. 20,678

6 Claims. (Cl. 177—311)

1

This invention relates to an indicating mechanism for use on cooking ranges by which one can tell at a glance whether or not a burner or heating element is operating. The mechanism is applicable to either gas or electric ranges. This application is a continuation in part of my co-pending application Serial No. 555,581, filed September 23, 1944, now abandoned.

The invention contemplates the use of a ring or disc which surrounds the valve stem by which the operation of a top burner of a range is controlled, and which is illuminated when the burner is turned on. The ring or disc may be made of glass or any other suitable translucent material and is disposed against the front of the range behind a valve operating handle. A small electric bulb is fastened in position to throw light on the back of the ring or disc when the bulb is energized. The energization of the bulb is controlled by a suitable switch which in turn is operated by the rotation of the valve stem.

The principal object of the invention is to provide a single effective and ornamental mechanism for indicating the condition of the top burners of a cooking range.

Other and more limited objects of the invention will be apparent from the following specification and the accompanying drawings forming a part thereof wherein—

Fig. 1 is a front elevation of a gas cooking range having my invention applied thereto;

Fig. 2 is an enlarged horizontal section taken on the line 2—2 of Fig. 1;

Fig. 3 is a vertical section taken on the line 3—3 of Fig. 2;

Fig. 4 is an enlarged front elevation of one of the indicating rings or discs and the valve operating handle associated therewith;

Fig. 5 is a sectional elevation showing one of the electric bulbs and the control switch therefor, the plane of the section being indicated by the line 5—5 of Fig. 2;

Fig. 6 is a view similar to Fig. 3 showing a modified form of my invention;

Fig. 7 is a front elevation of the indicator and valve operating handle shown in Fig. 6;

Fig. 8 is a detail view of a rotatable disc used in the construction shown in Figs. 6 and 7; and

Fig. 9 is a view similar to Fig. 6 showing a further modification of my invention.

Referring now to the drawings by reference characters, the numeral 1 indicates generally a gas cooking range of the divided top type wherein a pair of gas burners 2 are mounted one behind the other adjacent each side of the range.

2

The burners 2 are located in top burner compartments 3 and have suitable utensil supporting grates 4 disposed over them. The top 5 has a splasher plate 6 extending upwardly from the rear edge thereof. Beneath each of the burner compartments 3 is a storage compartment which is closed by a door 7. Between the burner and storage compartments is an oven and a broiler compartment which are closed by doors 8 and 9 respectively. The numerals 10 and 11 indicate handles by which the doors 8 and 9 are opened and closed. A pair of escutcheon plates 12 are removably secured to the front walls 13 of the top burner compartments 3 above the doors 7.

Gas is supplied to the burners 2 from a common manifold 14 through valves 15 which control the operation of the burners, there being provided a separate valve for each burner. The valves 15 are suitably secured to the manifold 14 which is held in place by suitable means, not shown. Each valve 15 has an operating stem 16 which extends forwardly from its valve through an opening 17 in the wall 13 and an enlarged opening 18 in the escutcheon plate 12. The outer end of each valve 20 stem 16 has a flattened portion 19 and is slotted as indicated at 20. An operating handle generally indicated by the numeral 21, through which the valve stem 16 is rotated to open and close the valve 15, is frictionally secured to the outer end of each valve stem 16, so that it can be readily removed and replaced as desired. The flattened portions 19 of the valve stems 16 which cooperate with complementary flattened portions in sockets 22 of the handles 21 assure the rotation of the 30 valve stems when the handles 21 are turned. The slots 20 enable the valve stems 16 to frictionally engage the walls of the sockets 22 with sufficient force to retain the handles 21 in place upon the valve stems 16 during normal operation. The handles 21 are molded from opaque plastic material and each comprises a dome-shaped body portion 23, having a cylindrical base 24, and an outwardly extending centrally disposed flat sided narrow section 25 by which the handle 21 is adapted to be grasped and turned.

A circular disc 26 having an outwardly extending ring-shaped annular flange 27 and a central aperture 28 is loosely mounted upon each valve stem 16 between the handle 21 and the escutcheon plate 12, the valve stem 16 extending through the aperture 28. The discs 26 are made of colored glass or any other suitable translucent material, preferably colored, and the outside diameters thereof are just slightly greater than the diameter of the openings 18 through the escutcheon

plates 12. The base 24 of each handle 21 is disposed within the ring-shaped annular flange 27 so that substantially all of the disc 26 is covered by the opaque handle 21 except the ring-shaped flange 27. The discs 26 are resiliently held against the escutcheon plates 12 by light helical springs 33 which are disposed around the stems 16 between the discs 26 and handles 21.

A small electric bulb 29 and a switch 30 are operatively associated with each disc 26. The bulbs 29 and switches 30 are mounted in casings 31 which are secured to the wall 13 behind the escutcheon plates 12. The valve stems 16 extend through the casings 31 and are adapted to open and close the switches 30 when they are turned. When the valves 15 are closed the flattened portions 19 of the valve stems 16 lie parallel to and closely adjacent the upper ends of buttons 32, and when the valve stems are rotated the rounded parts of the stems cam the buttons downwardly closing the switches 30 and energizing the bulbs 29. As is clearly shown in Figs. 2 and 3, the bulbs 29 are so positioned with respect to the opening 18 that they will, when energized, project light through the openings 18 against and through the translucent discs 26. Due to the fact that all of the discs 26 except the ring-shaped flanges 27 thereof are covered by the opaque handles 21, light will shine only through the flanges 27 which will be brightly illuminated whenever the valves 15 are turned on. By having the discs 26 and the flanges 27 thereof made from colored glass or plastic, especially red, they can be readily seen and will present a pleasing appearance whenever the valves are turned on, so that one can tell at a glance which of the burners 2 are operating.

In Figs. 6, 7 and 8 I have shown a slightly modified form of my invention. In this form of the invention I secure a disc 40 in the outer end of a cylindrical sleeve 41 which surrounds the opening 18 in an escutcheon plate 12, and is held from turning by a pair of tongues 42 which engage in slots 43 in the escutcheon plate. A narrow operating handle 44 which is frictionally held upon the outer end of the valve stem 16 retains the sleeve 41 and disc 40 in place. The lower half 45 of the disc 40 is opaque and the upper half thereof is translucent. The upper half of the disc is divided into three sections 46, 47 and 48 which are preferably of different contrasting colors. Rigidly secured to the valve stem 16 behind the disc 40 is an opaque disc 49 having a window 50 therethrough. A case 31 having a bulb 29 and switch 30 therein is mounted between the wall 13 and the escutcheon plate 12 in position for the bulb when energized to project light through the opening 18 in the escutcheon plate 12 and the window 50 in the disc 49. As shown in Fig. 6 the case 31 is secured to ears 51 on the valve 15 instead of to the wall 13 as shown in Figs. 2 to 4. As the valve stem is turned clockwise to open the valve 15, the bulb 29 is energized and the window 50 is brought successively behind the translucent sections 46, 47 and 48 of the disc 40. Light will shine through the window 50 and illuminate the section behind which it happens to be located and thus indicate whether the burner is operating at low, medium or high flame.

In Fig. 9 I have shown a further modification of my invention. This form of the invention is very similar to the form shown in Figs. 6 to 8, the various parts being identical but arranged somewhat differently with respect to each other.

In this form of the invention the disc 40 is secured to the sleeve 41 adjacent the operating handle 44, and the ring or disc 40 is rigidly secured to the operating stem 16 rearwardly of the disc 49. The window 50 is preferably disposed above the stem 16 as shown. As the valve stem 16 is turned clockwise to open the valve 15, the bulb 29 is energized and the translucent portion of the disc 40 is brought up behind the window 50. Light will then shine through the translucent portion of the disc 40 and through the window 50, indicating that the burner is operating.

When the invention is used with an electric range the stems 16 operate suitable switches which control the operation of the heating elements.

The construction and arrangement of the switch 30 and bulb 29 in the case 31 per se form no part of the present invention, but are claimed in the co-pending application of Robert G. Shiedler, Serial No. 20,614, filed April 13, 1948.

From the foregoing it will be seen that I have provided a very simple, effective and ornamental mechanism for accomplishing the objects of my invention. It is to be understood that I am not restricted to the specific construction shown and described herein as various modifications may be made thereto within the scope of the appended claims.

Having thus described my invention, I claim:

1. In an indicating mechanism for visually indicating the condition of a range heating element, the combination of an enlarged aperture through a front wall of the range, an operating stem through which the operation of the heating element is controlled projecting out through said aperture, an operating handle removably secured to the outer end of said operating stem, a translucent indicator disc loosely mounted upon said operating stem between said operating handle and the front wall of the range in position to cover said aperture, an electric bulb disposed behind said front wall in position to project light when energized through said aperture and said indicator disc, and means operative when said heating element is in operative condition to energize said electric bulb, said operating handle having a circular opaque base of slightly less diameter than the diameter of said indicator disc, said circular base being disposed closely adjacent said indicator disc whereby only a narrow ring of light is visible when said bulb is energized.

2. In an indicating mechanism for visually indicating the condition of a range heating element, the combination of an enlarged aperture through a front wall of the range, an operating stem through which the operation of the heating element is controlled projecting out through said aperture, an operating handle removably secured to the outer end of said operating stem, a translucent indicator disc loosely mounted upon said operating stem between said operating handle and the front wall of the range in position to cover said aperture, an electric bulb disposed behind said front wall in position to project light when energized through said aperture and said indicator disc, and means operative when said heating element is in operative condition to energize said electric bulb, said translucent indicator disc having a cylindrical recess therein of slightly less diameter than the diameter of said indicator disc, and said operating handle having a circular opaque base disposed within said recess

5

whereby only a narrow ring of light is visible when said bulb is energized.

3. In an indicating mechanism for visually indicating the condition of a range heating element, the combination of an enlarged aperture through a front wall of the range, an operating stem through which the operation of the heating element is controlled projecting out through said aperture, an operating handle removably secured to the outer end of said operating stem, a translucent indicator disc loosely mounted upon said operating stem between said operating handle and the front wall of the range in position to cover said aperture, an electric bulb disposed behind said front wall in position to project light when energized through said aperture and said indicator disc, and means operative when said heating element is in operative condition to energize said electric bulb, said translucent disc having an annular flange extending outwardly therefrom, and said operating handle having an enlarged base disposed within said flange and substantially filling the space within said flange whereby light is visible only through said flange when said bulb is energized.

4. In an indicating mechanism for visually indicating the condition of a range heating element, the combination of an enlarged aperture through a front wall of the range, an operating stem through which the operation of the heating element is controlled projecting out through said aperture, an operating handle removably secured to the outer end of said operating stem, a translucent indicator disc loosely mounted upon said operating stem between said operating handle and the front wall of the range in position to cover said aperture, an electric bulb disposed behind said front wall in position to project light when energized through said aperture and said indicator disc, and means operative to control the energization of said electric bulb, said means comprising a switch and cooperating connections between said switch and said operating stem through which said switch is opened and closed by the rotation of said operating stem, said operating handle having a circular opaque base of slightly less diameter than the diameter of said indicator disc, said circular base being disposed closely adjacent said indicator disc whereby only a narrow ring of light is visible when said bulb is energized.

5. In an indicating mechanism for visually indicating the condition of a range heating element, the combination of an enlarged aperture through a front wall of the range, an operating stem through which the operation of the heating element is controlled projecting out through said aperture, an operating handle removably secured to the outer end of said operating stem, a trans-

6

lucent indicator disc loosely mounted upon said operating stem between said operating handle and the front wall of the range in position to cover said aperture, an electric bulb disposed behind said front wall in position to project light when energized through said aperture and said indicator disc, and means operative when said heating element is in operative condition to energize said electric bulb, said translucent disc having an annular flange extending outwardly therefrom, and said operating handle having an enlarged base disposed within said flange and substantially filling the space within said flange whereby light is visible only through said flange when said bulb is energized.

6. In an indicating mechanism for visibly indicating the condition of a range burner, the combination of an escutcheon plate removably secured to said range, an enlarged aperture through said escutcheon plate, a valve by which the operation of said burner is controlled, a valve stem by which said valve is opened and closed projecting from said valve out through said aperture, an operating handle removably secured to the outer end of said valve stem, a translucent indicator disc loosely mounted upon said valve stem between said operating handle and said escutcheon plate in position to cover said aperture, an electric bulb mounted behind said escutcheon plate in position to project light when energized out through said aperture and said translucent indicator disc, and means operative to control the energization of said bulb, said means comprising a switch and cooperating connections between said switch and said valve stem through which said switch is opened and closed by the rotation of said valve stem, said translucent disc having an annular flange extending outwardly therefrom, and said operating handle having an enlarged base disposed within said flange and substantially filling the space within said flange whereby light is visible only through said flange when said bulb is energized.
